CARPET COMPANY, OF CLINTON, MASSACHUSETTS.

SPECIFICATION forming part of Design No. 17,771, dated October 11, 1887.

Application filed September 8, 1887. Serial No. 249,186. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is adapted for the border of a

stair-carpet. It has on its inner margin a row of small ornamental figures, and also an outer margin ornamented with line-work. The middle portion is divided into sections by vertical 20 rows of small ornaments. Each section is filled with a star-shaped group of flower forms having a flower form at the center encircled by other star-shaped flower forms.

What I claim as new, and desire to secure by 25 Letters Patent, is—

The design for a carpet-border, consisting of the design substantially as shown.
